(57) **CLAIM**

The ornamental design for a hat, substantially as shown and described.

DESCRIPTION

FIG. 1 is a rear perspective view of a hat according to the present disclosure, shown without laces for clarity of illustration;

FIG. 2 is a rear perspective view of the hat of FIG. 1 according to the present disclosure, shown with laces;

FIG. 3 is a top plan view of the hat of FIG. 2 according to the present disclosure;

FIG. 4 is a top plan view of the hat of FIG. 1 according to the present disclosure;

FIG. 5 is a side elevation view of the hat of FIG. 1 according to the present disclosure;

FIG. 6 is a side elevation view of the hat of FIG. 2 according to the present disclosure; and,

FIG. 7 is a front perspective view of the hat depicted in FIGS. 1-6 according to the present disclosure.

The broken lines in the drawings represent environmental subject matter that forms no part of the claimed design.
